Primary Examiner—Nanda Bondade*Attorney, Agent, or Firm*—Alix, Yale & Ristas, LLP[57] **CLAIM**The ornamental design for a bumper mounted loud-speaker,
as shown and described.**DESCRIPTION**FIG. 1 is a top plan view of a bumper mounted loud-speaker
showing my new design;

FIG. 2 is a front elevational view thereof;

FIG. 3 is a side elevational view thereof, the opposite side
being a mirror image;

FIG. 4 is a bottom plan view thereof; and,

FIG. 5 is a perspective view thereof.

The appearance of my new design, as viewed from the rear,
forms no part of the claimed design.**1 Claim, 3 Drawing Sheets**FIG. 1
